UNITED STATES PATENT OFFICE.

HENRY H. GOVE, OF BIDDEFORD, MAINE.

DESIGN FOR A FLUSHING DEVICE.

50,683.

Specification for Design.

Patented May 1, 1917.

Application filed March 19, 1915. Serial No. 15,625. Term of patent 14 years.

To all whom it may concern:

Be it known that I, HENRY H. GOVE, a citizen of the United States, residing at Biddeford, in the county of York and State of Maine, have invented a new, original, and ornamental Design for Flushing Devices, of which the following is a specification, reference being had to the accompanying drawing, forming part thereof.

The figure is a view in perspective of a flushing device showing my new design.

I claim:

The ornamental design for a flushing device, as shown.

HENRY H. GOVE.

Witnesses:

FRANK A. HOBBS,
JOSEPHINE H. BRADFORD.
